UNITED STATES PATENT OFFICE.

RASMUS P. NEDERGAARD, OF PORTLAND, OREGON.

DOOR-HINGE MARKER.

1,118,570.

Specification of Letters Patent. Patented Nov. 24, 1914.

Application filed July 30, 1913. Serial No. 782,102.

To all whom it may concern:

Be it known that I, RASMUS P. NEDERGAARD, a citizen of the United States, residing at Portland, in the county of Multnomah and State of Oregon, have invented certain new and useful Improvements in Door-Hinge Markers; and I do hereby declare the following to be a full, clear, and exact description of the invention, such as will enable others skilled in the art to which it appertains to make and use the same.

My invention relates to improvements in door hinge markers, and resides in the provision of adjustable cutting or marking blades and means for insuring the proper spaced relationship of the hinge with relation to the edges of the door.

An important object of my invention is to construct a device of the above mentioned character arranged and constructed to provide for the adjustment of certain of the marking or cutting blades, and employing means enabling the edge of the hinge to be properly spaced with relation to the door edge, which may be moved out of operative position when it is desired.

A further important object of my invention is to provide a device of the above mentioned character constructed of few parts and arranged so that certain of the parts which may have become worn may be readily replaced, which is cheap to manufacture, and reliable in its operation.

The above and additional objects are accomplished by such means as are illustrated in the accompanying drawings, described in the following specification, and then more particularly pointed out in the claims which are appended hereto and form a part of this application.

With reference to the drawings, wherein I have illustrated the preferred embodiment of my invention as it is reduced to practice, and throughout the several views of which similar reference numerals designate corresponding parts: Figure 1 is a perspective view illustrating my device in its assembled position. Fig. 2 is a longitudinal sectional view taken on line 2—2 of Fig. 1 showing the means for adjustably securing the cutting or marking blades, and Fig. 3 is a transverse sectional view taken on line 3—3 of Fig. 1, illustrating the manner of mount-

ing the guide plate forming a part of my invention.

Referring now to the drawings, the numeral 1 designates as an entirety the body portion of my device, which is rectangular in shape and may be constructed of any suitable material.

As a means for supporting the body portion this invention employs a rectangular block 2 having a handle 3 secured centrally thereto on one side thereof, and secured to the body portion 1 by means of a bolt 4 extending centrally through the body portion 1 and the block 2.

The body portion 1 of my device is provided upon its outer surface with a plurality of transverse slots 5 which are formed in pairs adjacent each end of the body portion and are adapted to receive cutting or marking blades 6 and 7. The transverse slots 5 of each pair are disposed in spaced relationship, and when it is desired to mark the designated space for a smaller hinge, the blades 6 and 7 are inserted within the slots 5 nearest to the center of the body portion.

As a means for removably securing the blades 6 and 7 within the slots 5 this invention employs countersunk pins 8 which extend transversely through the slots of each pair and the blades centrally thereof from the ends of the body portion, and are enlarged and threaded, to engage the threaded portion of the opening through which they extend.

A longitudinal cutting or marking blade 10 is mounted within a longitudinally extending slot 10' formed in the upper surface of the body portion 1 in spaced relationship with the adjacent edge thereof, for a distance equivalent to the desired spaced relationship of the longitudinal edge of the hinge to the door edge. The longitudinal cutting or marking blade 10 coacts with the blades 6 and 7 in the operation of marking the door.

As a means for enabling the longitudinal mark with which the longitudinal edge of the hinge is to register to be spaced with relation to the longitudinal edge of the door, this invention employs a guide plate 11 which is slidably mounted upon the side edge of the body portion 1 adjacent the

longitudinal blade 10. The guide plate 11 is of the same length as the body portion 1 and block 2, and is provided with an inwardly extending lateral flange 12 which is adapted to engage the adjacent wall of the block 2 during the sliding operation of the guide plate 11. Mounted upon the flange 12 is a pair of spaced pins 13 which engage the inner surface of the plate 11 and extend outwardly from the flange and terminate in spaced relationship with the outer longitudinal edge of the plate 11.

As a means for securing the plate 11 to the body portion 1, this invention provides a downwardly extending flange 14 formed on the under surface of the body portion 1 and engaging the adjacent wall of the block 2. A pair of spaced openings 15 is formed through the flange 14 of the body portion 1, said openings being adapted to receive the pins 13 secured to the flange 12 of the plate 11, whereby the plate 11 is slidably secured to the body portion 1. The sliding movement of the plate 11 with relation to the body portion 1 is limited by the engagement of the flange 12 with a laterally extending flange 16 formed on the block 2 and with the flange 14, inasmuch as the flange 12 operates therebetween, as will be clearly seen in Figs. 1 and 3.

In operation, the guide plate 11 is moved to its extended position so that its outer edge will be beyond the outer edges of the blades 6, 7 and 10, and placed into engagement with the side of a door whereby the desired spacing of the cut to be made by the longitudinal blade 10 is provided. The handle portion 3 is then struck a blow with a mallet or any other suitable tool, causing the cutting or marking blades to cut into the wood and thereby make the desired mark. As hereinbefore stated, the transversely extending blades 6 and 7 may be adjusted after the manner described when it is desired to designate or mark a space for a small hinge.

It is apparent that my device may be used for other marking purposes, and in such event the guide plate 11 may be moved to a position to enable the device to be placed in any desired position upon the object to be marked. The action of the plate 11 will be automatic, inasmuch as it is loosely mounted after the manner described upon the body portion 1. When the device is placed upon a flat surface the blade 11 is forced to its inwardly extending position and out of the way.

In reduction to practice, I have found that the form of my invention, illustrated in the drawings and referred to in the above description, as the preferred embodiment, is the most efficient and practical; yet, realizing that the conditions concurrent with the adoption of my device will neces-

sarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim is:

1. In a device of the character described, a rectangular body portion, marking blades mounted thereon, a rectangular plate slidably mounted upon said body portion, a laterally extending flange formed upon one of the longitudinal edges of said plate, a rectangular block for supporting said body portion, and means for limiting the sliding movement of said plate comprising flanges formed on said body portion and supporting block adapted for engagement with the said flange formed on said plate.

2. In a device of the character described, the combination with a rectangular body portion having a plurality of transverse slots and a single longitudinal slot formed therein of marking blades mounted within certain of the transverse slots and the longitudinal slot, means for detachably securing said blades within said transverse slots, a rectangular guide plate mounted upon the body portion, a laterally extending flange formed on one of the longitudinal edges of said plate, a rectangular block for supporting said body portion and means for limiting the sliding movement of said plate comprising flanges formed on said body portion and the supporting block adapted for engagement with the flange formed on said plate.

3. In a device of the character described the combination with a rectangular body portion of marking blades mounted thereon, two of said marking blades being mounted adjacent the ends of the body portion and the other of the marking blades being mounted adjacent one of the longitudinal edges of the body portion, means for disposing the end marking blades in different spaced relation to each other, a plate slidably mounted upon the body portion, a laterally extending flange formed on the plate, a rectangular block supporting said body portion, a handle member carried by the block, a flange formed on said block, a flange formed on the body portion and disposed in spaced relation to the flange on the block and the flange on said plate adapted for engagement with the flanges on the block and on the body portion to limit the sliding movement of the plate.

4. In a door hinge marker, a rectangular supporting block, a rectangular body portion mounted upon the supporting block, a handle carried by the supporting block, marking blades mounted upon the body

portion, means for permitting changing the spaced relation of certain of the marking blades, means for spacing one of said marking blades from the edge of a door and slidably mounted upon one of the longitudinal edges of the body portion, flanges formed on the supporting block and body portion and disposed in spaced relation to each other and a flange carried by said last

5 named means slidably mounted between the 10 first named flanges to limit the movement of the last named means.

In testimony whereof I affix my signature in presence of two witnesses.

RASMUS P. NEDERGAARD.
